UNITED STATES PATENT OFFICE.

WATSON B. STOCKMAN, OF CHESTER, PENNSYLVANIA.

DILUTING DEVICE FOR INTERNAL-COMBUSTION ENGINES.

Application filed December 30, 1920. Serial No. 434,167.

To all whom it may concern:

Be it known that I, WATSON B. STOCKMAN, a citizen of the United States, residing at Chester, in the county of Delaware and State of Pennsylvania, have invented certain new and useful Improvements in Diluting Devices for Internal-Combustion Engines, of which the following is a specification.

This invention relates to an improved fuel mixture diluting device for motor vehicle engines and has as one of its principal objects to provide a device whereby heated air may be introduced into the fuel mixture of an engine for aiding the vaporization of the mixture.

The invention has as a further object to provide a device wherein, if desired, cold air may be introduced into the fuel mixture for cooling the engine cylinders.

20 A still further object of the invention is to provide a device which may be controlled from the instrument board of the vehicle.

The invention has as a further object to provide a device employing a distributor which may be interposed between the engine intake manifold and the carburetor for introducing air into the manifold.

And the invention has as a still further object to provide a device which may be readily installed and which may be employed in connection with substantially any conventional design of internal combustion engine.

Other and incidental objects will appear hereinafter.

35 In the drawings:

Figure 1 is a side elevation showing a motor vehicle engine equipped with my device.

40 Figure 2 is a perspective view showing the device detached.

Figure 3 is a fragmentary section particularly illustrating the heater and control valve employed.

45 Figure 4 is a longitudinal sectional view of the valve employed.

Figure 5 is a detail section on the line 5—5 of Figure 4, looking in the direction of the arrows.

50 Figure 6 is a fragmentary section of the priming valve employed.

Figure 7 is a detail section of the distributor employed.

55 Figure 8 is a detail section on the line 8—8 of Figure 7, looking in the direction of the arrows, and

Figure 9 is a detail perspective view of the control member employed.

For convenience, I have, in the drawings, shown my improved device in connection with a motor vehicle engine 10 of conventional design. The intake manifold of the engine is indicated at 11 while the engine carburetor is indicated at 12. At 13 is shown the exhaust manifold of the engine. In carrying the invention into effect, I employ 60 a hollow concavo convex heater 14. This heater may be formed of suitable sheet metal and is curved to fit over the exhaust manifold 13 resting thereon. Secured to said heater is a bracket 15, the inner end 65 portion of which projects over the engine head and engaged through said bracket is one of the bolts securing the head. Thus, the heater will be securely held in position. Extending from the heater is a discharge 70 pipe 16 provided, as particularly shown in Figure 6, with a collar 17 while adjacent said collar the pipe is formed with an opening 18. Slidable upon the pipe to normally abut the collar overlying said opening, is a 80 sleeve valve 19. The purpose of this structure will later appear.

Connected to the pipe 16 at its outer end is the control valve employed. As best shown in Figures 3 and 4 of the drawings, 85 this valve includes a cylindrical casing 20 closed at one end and threaded upon the opposite end of the casing is a cap 21. Depending from the casing is a nipple 22 having a passage 23 therethrough while at its upper side, at a point opposite said passage, the casing is provided with a cold air inlet opening 24. Freely slidable within the casing is a tubular valve 25 open at its ends and connected with said valve is a stem 26. 90 which, as shown in detail in Figure 5, is formed with flat sides to coact with the cap 21 of the valve casing for holding the valve against rotation. The stem is connected with the valve by a transverse pin 27 extending through the inner end portion of said stem and bearing between said pin and the cap 21 is a spring 28 surrounding the stem and normally holding the valve closed. Formed in the valve at its upper and lower 100 sides are openings 29 adapted to coincidentally register one with the opening 24 and the other with the passage 23 of the valve casing and, as best shown in Figure 4, the valve is further provided with openings 30 110

and 31 respectively. The opening 30 is adapted to register with the inlet passage of the casing leading from the pipe 16 while the opening 31 is adapted to coincidentally register with the outlet passage 23. Threaded upon the outer end of the valve stem 26 is a head 34 upon which is pivoted a ring 35 and swiveled upon said ring is an eye 36 to which is connected one end of a control 10 wire or cord 37. Mounted upon the instrument board of the vehicle or at any approved point, is the control member employed. As shown in detail in Figure 9, this member comprises a split tubular body 38 which is preferably formed of suitable resilient sheet metal and at the ends of the body are ears 39 through which may be engaged suitable fastening devices for securing the member in position. At one end of 15 the body is a pair of upstanding lugs 40 and journaled between said lugs is a pulley 41 over which the cord 37 is trained. Freely movable within the body is a tubular slide 42 to which the cord is connected and projecting from said slide freely through the slot at the forward side of the body, is a handle 43. Formed in the body at the lower side of the slot therein are spaced notches 44 and 45 respectively. As will be perceived, 20 the head 34 may be adjusted upon the valve stem 26 for varying the effective length of the cord.

Connected to the nipple 22 of the valve casing is a cut-off valve 32 of approved design and extending from said valve is a pipe 33 to the lower end of which is attached the distributor employed. As best shown in Figures 7 and 8, this distributor comprises a relatively thin body 46 which is provided with flat sides and is shaped to fit between the confronting flanges of the intake manifold 11 and carburetor 12, openings 47 being provided in the body for receiving bolts or other fastening devices connecting the carburetor with the manifold so that said carburetor will also serve to hold the distributor in position. The body is formed with a central opening therethrough disposed to register with the passages of the carburetor and manifold and surrounding said opening is an annular distributing chamber 48 closed by a distributing ring 49 snugly but removably fitting in said opening. Through the ring is formed an annular series of discharge openings 50 and overlying the ring at opposite ends thereof are mixing screens 51 suitably secured to the end edges of the ring. At one end the body 46 is formed with an upstanding nipple 52 threaded upon the lower end of the pipe 33 and leading from said nipple to the chamber 48 are diverging passages 53.

As will now be readily understood, the spring 28 of the control valve will normally hold said valve closed to cut off communica-

tion between the heater 14 and the distributor, the slide 42 of the control member being in the position shown in Figure 9. By moving this slide toward the left and rotating the slide to engage the handle 43 thereof in the notch 44, the valve 25 may be shifted to a position having the opening 30 therein registering with the inlet passage of the casing and the opening 31 registering with the outlet passage 23. Engine suction in the manifold 11 will then serve to draw hot air from the heater into and through the distributor to be discharged into the manifold. The heated air drawn into the distributor will, of course, fill the chamber 48 whence the heated air will flow in jets through the series of openings 50 into the transverse passage of the distributor between the screens 51. The fuel mixture flowing from the carburetor, upon passing through the first of these screens will be broken up thereby and in this state will be pierced by the jets of heated air flowing from the openings 50. The jets of heated air will thus tend to supply the mixture with heat, so that the mixture will be effectually vaporized and the temperature thereof appreciably raised. Upon passing through the other of the screens into the intake manifold, the mixture will then be further broken up and its particles commingled so that a homogenous fuel supply will be delivered to the engine cylinders. By moving the slide 42 of the control member still further to the left and engaging the handle 43 thereof in the notch 45, the valve 25 will then be moved to the position shown in Figure 4 having the openings 29 therein registering with the opening 24 of the valve casing and with the outlet passage 23 respectively. The engine suction in the manifold will then serve to draw in cold air through the valve and through the distributor into the manifold. The valve 32 is provided so that should the control valve become disabled, communication between the valve and distributor may be cut off.

Attention is now again directed to Figure 6. As will be perceived in view of the preceding, the valve 19 provides means whereby heated air drawn from the heater 14 may be diluted with cold air. This may be accomplished simply by shifting the valve along the pipe 16 to uncover the opening 18. Further, in cold weather, a suitable priming fluid may be introduced into the pipe 120 through said opening to be thence drawn into the intake manifold of the engine. The purpose of the opening 18 and valve 19 therefore becomes apparent.

Having thus described the invention, what is claimed as new is:

1. A device of the character described including a heater, a distributor, a pipe connecting the heater with the distributor, a valve casing interposed in said pipe and

provided with an atmospheric air port and passages for said pipe, and a tubular valve 5
slidable in said casing and provided with corresponding ports and passages for controlling communication with the distributor from the atmospheric air and the heater respectively, said tubular valve being adapted to normally close all of said ports and 20
passages, and a control member for said tubular valve, a resilient casing for said member provided with a longitudinal slot and side notches opening into said slot, a handle on 25
said member adapted to run in said slot and register with said notches, thereby positioning said tubular valve to open communication with said distributor from said heater or from the atmospheric air respectively.

2. A device of the character described including a heater, a distributor, a pipe connecting the heater with the distributor, a valve casing interposed in said pipe and provided with an atmospheric air port and 15
passages for said pipe, and a tubular valve 15
slidable in said casing and provided with

corresponding ports and passages for controlling communication with the distributor from the atmospheric air and the heater respectively, said tubular valve being adapted to normally close all of said ports and 20
passages, and a control member for said tubular valve, a resilient casing for said member provided with a longitudinal slot and side notches opening into said slot, a handle on 25
said member adapted to run in said slot and register with said notches, thereby positioning said tubular valve to open communication with said distributor from said heater or from the atmospheric air respectively.

In testimony whereof I affix my signature.

WATSON B. STOCKMAN. [L. S.]
